UNITED STATES PATENT OFFICE

121,239

DESIGN FOR A BATHING SUIT

Mortimer Solomon, Brooklyn, N. Y.

Application March 7, 1940, Serial No. 90,741

Term of patent 3½ years

To all whom it may concern:

Be it known that I, Mortimer Solomon, a citizen of the United States of America, residing in Brooklyn, city of New York, county of Kings, and State of New York, have invented a new, original, and ornamental Design for a Bathing Suit, of which the following is a specification, reference being had to the accompanying drawing, forming part thereof.

Fig. 1 is a front view of a bathing suit showing my new design.

Fig. 2 is a rear view thereof.

I claim:

The ornamental design for a bathing suit, substantially as shown.

MORTIMER SOLOMON.
